UNITED STATES PATENT OFFICE.

HUGH M. SWEENEY, OF PROVIDENCE, RHODE ISLAND.

BOTTLE-STOPPER AND FASTENER THEREFOR.

SPECIFICATION forming part of Letters Patent No. 241,089, dated May 3, 1881.

Application filed September 27, 1880. (No model.)

To all whom it may concern:

Be it known that I, HUGH M. SWEENEY, a citizen of the United States, residing at Providence, in the county of Providence and State 5 of Rhode Island, have invented certain new and useful Improvements in Bottle-Stoppers for Aerated and other Liquids; and I do hereby declare the following to be a full, clear, and exact description of the invention, such as will 10 enable others skilled in the art to which it appertains to make and use the same, reference being had to the accompanying drawings, and to letters or figures of reference marked thereon, which form part of this specification.

15 This invention relates to improvements in bottle-stoppers for aerated and other liquids, and it is constructed, arranged, and carried out in a manner as will hereinafter be more fully shown and described, reference being had to 20 the accompanying drawings, in which—

Figure 1 represents a front elevation of the device as shown in position when the bottle is corked. Fig. 2 represents a side elevation of the device in the same position. Fig. 3 represents a side elevation of the device in an un- 25 locked position. Fig. 4 represents a plan view. Fig. 5 represents a perspective view of the bail-wire, and Fig. 6 represents a central longitudinal section of the rubber stopper and its metal- 30 lic head.

Similar letters refer to similar parts wherever they occur on the different parts of the drawings.

N represents the bottle, and N' its neck, as 35 usual. Around the neck of the bottle is secured the wire a a', that is provided with side extensions, a'' a'', that serve as fulcra for the bail-wire. The latter is made in one continuous piece, as shown at B in Fig. 5, and is composed of the semicircular lever b, the curved side extensions, c c', having curved slots c' c', embracing the fulcra a'' a'', and locking-recesses c'' c'', as shown. The upper part of the 40 said bail-wire passes upward as bent spring-bars d d, the inner ends, d' d', of which are adapted to rest loosely in the side perforations, e' e', in the upper part of the metallic head-piece e, (shown in Fig. 6.)

The lower part of the metallic piece e is pro- 45 vided with an annular groove, e'', around which

fits the elastic rubber stopper f, that is provided with an internal chamber, f', by which arrangement the said elastic stopper f is capable of being compressed vertically and allowed to expand laterally, so as to cover the mouth 55 of the bottle when the bail-wire is locked into position, as fully shown in Figs. 1 and 2.

The lower end of the elastic stopper f is preferably recessed at f'', for the purpose of allowing the pressure within the bottle, when the latter is corked, to act on said recessed end of the stopper, causing its annular edge f''' to be forced against the inside of the neck, and thereby to effect a very close connection, so as to prevent the escape of any portion of the con- 60 tents of the bottle.

The metallic head e is furthermore provided with the inclined faces e''' e''', as shown in Fig. 4, by which arrangement I am enabled to effect the interlocking of the upper ends, d' d', of the 65 bail-wire with the recesses e' e' in the said metallic piece e after the stopper is put in place at the neck of the bottle, simply by forcing the said ends of the bail-wire laterally on the inclined faces e''' e''' until the ends d' d' reach 70 the recesses e' e', when the spring of the bail-wire causes the ends d' d' to lock into the said recesses e' e', as shown.

To disconnect the upper ends, d' d', of the bail-wire from the metallic stopper-head e, it is 75 only necessary to expand them laterally far enough until removed from the recesses e' e', when the stopper may be entirely disconnected from the bottle. This is very desirable in the process of filling bottles with aerated liquids, 80 such as soda-water or similar gas-charged liquids; and for this purpose the exterior surface, F, of the elastic stopper is made as a vertical cylinder, so as to fit closely within the usual filling-cylinder of a bottling-machine, in a simi- 85 lar manner as ordinary corks are used, so as to enable it to be driven by the usual plunger on such machines into the neck of the bottle without allowing the gas-charged liquid to escape, and after the stopper is so driven the 90 bail-wire, as shown, can instantly be secured in a manner as described, and the whole locked into position, as fully shown in Figs. 1 and 2.

This improved device is equally useful for closing bottles containing lager-beer or other 95

beverages, and for such purposes it may not be necessary to disconnect the ends of the bail-wire from the metallic stopper-head.

I claim—

5 1. In a bottle-stopping device, the herein-described bail-wire B, made in one single piece, and composed of the semicircular lever b, the curved side extensions, c c, with their curved slots c' c' and locking-recesses c'' c'', and having its 10 upper spring ends, d d, bent laterally at d' d' and adapted to fit into the locking-recesses e' e' on the metallic stopper-head e, as and for the purpose set forth.

2. In combination with the stopper-head e, having an annular groove, e'', the cylindrical elastic stopper f, having an internal chamber, f', below the stopper-head and above that por-

tion of the stopper which is adapted to enter the bottle, as and for the purpose set forth and described.

20

3. In combination with the neck-wire a a' and its fulera a'' a'', the single-piece bail-wire B, composed of the semicircular lever b, the curved side extensions, c c, having curved slots c' c' and locking-recesses c'' c'', upper spring 25 ends, d d d' d', the head e, having inclined faces e''' e''', and locking-recesses e' e', substantially as set forth.

In testimony whereof I have affixed my signature in presence of two witnesses.

HUGH M. SWEENEY.
